DESIGN FOR A TRUCK BODY

Ralph H. Greegor, Columbus, Ohio, assignor to
General Door Company, Reno, Nev., a corpora-
tion of Nevada

Application May 8, 1936, Serial No. 62,556

Term of patent 14 years

To all whom it may concern:

Be it known that I, Ralph H. Greegor, a citizen
of the United States, residing at Columbus, in
the county of Franklin and State of Ohio, have
invented a new, original, and ornamental De-
sign for a Truck Body, of which the following
is a specification, reference being had to the ac-
companying drawing, forming a part thereof.

In the drawing:

Figure 1 is a side elevation of a truck body,
showing my new design;

Figure 2 is a front elevation thereof;
Figure 3 is a rear elevation thereof with the
doors open.

The dominant feature of my design is the
rolling door of the truck body, illustrated in Fig-
ure 1 of the drawing.

I claim:

The ornamental design for a truck body sub-
stantially as shown and described.

RALPH H. GREEGOR.
